DESIGN FOR A TEXTILE FABRIC

Sterling B. McDonald, Chicago, Ill.

Application January 4, 1938, Serial No. 74,093

Term of patent 7 years

To all whom it may concern:

Be it known that I, Sterling B. McDonald, a citizen of the United States, residing at 1805 Merchandise Mart, Chicago, in the county of Cook and State of Illinois, have invented a new, original, and ornamental Design for a Textile Fabric, of which the following is a specification, reference being had to the accompanying drawing, forming a part thereof.

The figure is a plan view of a textile fabric, showing my new design.

I claim:

The ornamental design for a textile fabric, substantially as shown.

STERLING B. McDONALD.
